UNITED STATES PATENT OFFICE.

GEORGE P. SALISBURY AND CHARLES W. FOSTER, OF NEW HAVEN, CONN.

FEED-WATER REGULATOR FOR STEAM-BOILERS.

SPECIFICATION forming part of Letters Patent No. 284,762, dated September 11, 1883.

Application filed May 22, 1883. (No model.)

To all whom it may concern:

Be it known that we, GEORGE P. SALISBURY and CHAS. W. FOSTER, citizens of the United States of America, residing at New Haven, in 5 the county of New Haven and State of Connecticut, have invented certain new and useful Improvements in Feed-Water Regulators for Steam-Boilers, of which the following is a specification, reference being had therein to the accompanying drawing, in which the figure, which is sectional in part, shows our improvement.

Our invention relates to improved means for supplying water to steam-boilers automatically, and in such a manner that the quantity of water in the boiler shall be uniform or very 15 nearly uniform.

To this end the invention consists in a valve which is operated by a knee or toggle joint in 20 connection with a float, as the invention is hereinafter more fully described and explained by reference to the drawing.

To enable others to make and use our improvement, we will give a detailed description 25 of the same.

A is a shell, of sheet metal, of the requisite thickness to insure sufficient strength, and may vary in form, the only requisite being that it be of such size as to inclose our improvement. 30 The pipes B and C connect the shell with the boiler, the pipe B connecting it with that portion of the boiler which is above the water-line, and the pipe C connecting it with that portion which is below the water-line.

The feed-water valve L is cylindrical in form, 35 and is free to move in the part G. It is pivoted to the end of the lever H in the manner shown, closes the port d, and its seat is on the part G. The lever H is bent at right angles 40 near its end, and the end is formed to make, in connection with the link e, a knee or toggle joint. As before stated, the valve is pivoted to the end of the lever, and so is the link e, which is also pivoted to the part G. Thus 45 constructed, as the float I descends, the link e moves toward the dotted line, the valve is drawn back from its seat, and the port d is opened. The other end of the lever H is fastened to the float I, which is preferably a 50 low sphere. We do not confine ourselves to

any particular form of feed-water valve, but prefer the form shown. The piece G is screwed onto the piece F, which connects it with the feed-water pipe D. It has a projection or part in which the valve L moves, and is extended and forms a support for one end of the link e. In this part the port d is formed. The piece F connects the feed-water pipe D with the piece G, which serves as a nut to hold the piece F to the shell A. From the passage in this piece 60 the valve a opens into the chamber c, which connects with the waste-water pipe E, which is made to connect with the water-tank, if need be, to prevent any waste of water. The pivoted lever J, having the weight K, operates 65 on the valve-stem b to hold the valve a to its seat. Water is forced through the feed-water pipe D by any suitable means—as, for example, a force-pump, injector, or in cities where the source of the water-supply is sufficiently 70 elevated to force water into steam-boilers, as is frequently the case, the feed-water pipe may be directly connected with the city water-pipe.

In our improvement a stream of water is kept continually running through the feed-water pipe while the boiler is in use, which is sufficient or a little more than sufficient to supply the boiler with water. The waste-valve a is also held to its seat by the means described, so that it will require a greater pressure to 80 raise it than the pressure of the steam in the boiler; or, in case a safety or blow-off valve is used, the valve a should be held to its seat, so that a greater pressure is required to open it than is required to open the safety-valve. 85

Constructed as above described and as shown, the operation of our feed-water supply is as follows: As the feed-water is continually forced through the feed-water pipe while the boiler is in use, and as the feed-water valve is opened 90 by the conversion of the water in the boiler into steam, or by its diminution from any cause, the feed-water enters the boiler, when the water in the same is low enough to open or partially open the feed-water valve, and 95 keeps the quantity of water in the boiler uniform or very nearly uniform, while any excess of water passes out through the waste valve and pipe.

We are well aware that many contrivances 100

have been made to keep the quantity of water in boilers uniform by their automatic action; but

What we claim as our invention, and desire 5 to secure by Letters Patent, is—

The feed-water valve L, link e, lever H, and float I, in combination with suitable means for forcing water into the boiler, and with the waste-water valve a, held to its seat by the 10 weighted lever J, as described, whereby the

quantity of water in the boiler is kept nearly uniform, all arranged as set forth.

In testimony whereof we affix our signatures in presence of two witnesses.

GEORGE P. SALISBURY.
CHAS. W. FOSTER.

Witnesses:

GEORGE TERRY,
FRANK P. SMITH.
